UNITED STATES PATENT OFFICE.

ANTON TAMULAITIS, OF CHICAGO, ILLINOIS.

DESIGN FOR A CABINET.

No. 38,586.

Specification for Design.

Patented May 28, 1907.

Application filed April 19, 1907. Serial No. 369,183. Term of patent 7 years.

To all whom it may concern:

Be it known that I, ANTON TAMULAITIS, a subject of the Czar of Russia, residing at Chicago, in the county of Cook and State of Illinois, have invented a new, original, and ornamental Design for Cabinets, of which the following is a specification, reference being had to the accompanying drawing, forming a part thereof.

The drawing is a perspective view showing the design of the cabinet.

What I claim is:

The ornamental design for a cabinet, as shown.
